The characteristic feature of my design resides in the lower pocket that blends around and tapers into the sides of the golf bag, all as shown.

I claim:

The ornamental design for a golf bag, substantially as shown and described.
